John Ballord Wills,
By J. P. Cooley,
attorney.

UNITED STATES PATENT OFFICE.

JOHN BALLARD WILLS, OF PITTSBURGH, PENNSYLVANIA, ASSIGNOR OF ONE-THIRD TO
DAVID W. BROBECK, OF PITTSBURGH, PENNSYLVANIA.

GRIPPER FOR PRINTING-PRESSES.

1,324,946.

Specification of Letters Patent.

Patented Dec. 16, 1919.

Application filed July 17, 1918. Serial No. 245,281.

To all whom it may concern:

Be it known that I, JOHN BALLARD WILLS, a citizen of the United States, and resident of Pittsburgh, in the county of Allegheny 5 and State of Pennsylvania, have invented a new and useful Improvement in Grippers for Printing-Presses; and I do hereby declare the following to be a full, clear, and exact description thereof.

10 My invention relates to attachments for printing presses, and has special reference to an attachment for use in connection with the usual form of grippers on platen printing presses.

15 The main object of my invention is to form a cheap, simple and efficient attachment for platen presses which will provide for forming a perfect grip on the sheet of paper on which the printing is to be done without 20 regard to the nature of such printing, and also in connection with the use of the usual and what is known as the perforating rule.

A further object of the invention is to 25 form such a gripper attachment which will act as a stripper for the perforating rule during the use of such rule, and also one which will prevent the paper from sticking during the printing on the same.

30 A still further object of the invention is to provide such a gripper attachment which will be firmly held in place when set, will not slip and will be adjustable for any size of sheet or form desired.

To these ends my invention consists, generally stated, in the novel arrangement, construction and combination of parts, as hereinafter more specifically set forth and described and particularly pointed out in the claims.

40 To enable others skilled in the art to which my invention appertains to construct and use my improved gripper attachment, I will describe the same more fully, referring to the accompanying sheet of drawings, in 45 which—

Figure 1 is a front plan view of a gripper applied to the slide of a platen printing press and having my improved attachment applied horizontally thereto;

50 Fig. 2 is a bottom plan view of the attachment;

Fig. 3 is a cross-section on the line 3—3 Fig. 1;

Fig. 4 is a bottom plan view of another form of the attachment; 55

Fig. 5 is a plan view of one of the usual forms of a perforating rule;

Fig. 6 is a front plan view of another manner of using the attachment; and

Fig. 7 is a cross-section on the line 6—6 60 Fig. 2 looking in the direction of the arrows.

Fig. 8 is a side elevation of a portion of a platen printing press showing the swinging bed, gripper and form member.

Like symbols of reference indicate 65 like parts in each of the figures of the drawings.

As illustrated in the drawings, A represents the slide on the swinging bed *a* of an ordinary platen printing press to which 70 the gripper B is applied, such gripper being provided with the two main supporting or side bars 1 which are secured at their inner ends to such slide by means of the bolts C passing through holes 2 in the heads 3 on 75 said bars and through a slot D in said slide. On each side edge of the side bars 1 is a groove 4 which is formed four sided or square shape and connected horizontally to such bars through such grooves, as herein-after described is the cross or extension attachment F. This attachment F extends across the gripper B and is formed with a double extension means by having two parallel rods 5 which are provided with heads 6 secured at each end and such heads are hollowed out at their bottom faces to form a seat 7 and flanges 7' for fitting over the side bars 1. A screw bolt 8 having a head 9 and a four side or square end 10 passes 80 through the outer end flange 7' of the heads 6 and such end 10 engages within the groove 4 in the outer end of the bars 1 to hold the attachment F in place, although if desired, such bolt can be placed on the inner side 85 of the heads 6, so that its square end will engage within the groove 4 on the inside edge of the bars 1, as shown in Fig. 6.

The parallel rods 5 are each provided with a rod extension portion 11 and a tubular portion 12, with a rod portion and a tubular extension portion on each of the heads 6 and

such rod portions are adapted to enter the tubular portions and thus form a space 13 between the same. The rod portion 11 and tubular portion 12 may be formed square in 5 cross-section, as shown in section in Fig. 7.

In the use of the perforating rule E, such as is shown in Figs. 1 and 5, such rule is supported and locked in the chase or form member F of the press G in the usual manner, and in the operation of perforating the 10 paper, the rule will enter the space 13 formed between the parallel rods 5 of the attachment F with the knife or cutting edge e outward and thus perforate the paper, while 15 the operation of printing on the paper can also be performed in the usual manner and the paper held by a firm grip through the medium of the attachment. In this position the attachment can also be used for 20 gripping the sheet of paper to be printed without using the perforated rule E.

It will be obvious that my improved attachment F can be used separately from the 25 perforating rule E for gripping the sheet of paper to be printed, and that it can be attached as above described in a vertical position to the gripper B by cross-bars 14 supported at each end of the side bars 1 of the gripper B, as shown in Fig. 6, which cross-bars 30 are also attached to such bars 1 in the same manner as above described for the attachment F being made to the bars 1, while such attachment in this position can also be used with the perforated rule E.

As shown in Fig. 4 one of the heads 6 can be dispensed with and the rod portions 11 bent in a semi-circular form at its free end to form the rounded head as shown at 15, and such free end threaded as at 16, so that 40 a tubular portion having a like threaded end can be screwed on to the same for forming the two parallel rods, with the space 13 between the same for ruling. In such case such closed end 15 and tubular portion 12 45 will act to hold the sheet down at the end of the line and along the same while being ruled and also prevent blurring.

It will thus be seen that my improved attachment for printing presses can be easily 50 and cheaply manufactured and can be easily and quickly assembled and operated when desired, while such attachment will also be positive in its work, will always act to hold the sheet being printed or perforated, and 55 thereby act to prevent sticking of the sheet.

It will also be seen that the device can be easily and conveniently used and adjusted to 60 any position desired for the gripping of the paper or use of the perforating rule, and will be enabled to be firmly set on the gripper bars and at the position desired, while any number of the attachments can be used on the gripper and in both vertical and horizontal positions.

Various modifications and changes in the 65 design and construction of my improved attachment for platen printing presses, other than those described and shown, may be resorted to, without departing from the spirit of the invention or sacrificing any of its advantages.

What I claim as my invention and desire to secure by Letters Patent is:

1. The combination with the movable gripper bars of a platen printing press, of a 75 perforating rule mounted on the form member of the press, and cross-extension rods on said bars, comprising two parallel rod portions having a space formed between the same for allowing the perforating rule to 80 enter therein in the movements of said rod portions, said rod portions thus acting to grip and strip the paper from the rule.

2. The combination with the movable gripper bars of a platen printing press, of a 85 perforating rule mounted on the form member of the press, and cross-extension rods on said bars, comprising two parallel rod portions having a space formed between the same for allowing the perforating rule to 90 enter therein in the movements of said rod portions, said rod portions being formed square in cross-section and acting to grip and strip the paper from the rule.

3. The combination with the movable 95 gripper bars of a platen printing press, of a perforating rule mounted on the form member of the press, and cross-extension rods on said bars, comprising two parallel rod portions having a space formed between the 100 same for allowing the perforating rule to enter therein in the movements of said rod portions, said rod portions being formed square in cross-section and having a tubular portion formed square in cross-section fitting over the same, and such rod portions 105 acting to grip and strip the paper from the rule.

4. The combination with the movable gripper bars of a platen printing press, of a 110 perforating rule mounted on the form member of the press, and cross-extension rods on said bars, comprising two parallel rod portions having a space formed between the same for allowing the perforating rule to 115 enter therein in the movements of said rod portions, said rod portions having head portions for holding the same together and said rod portions being formed square in cross-section and having tubular portions formed 120 square in cross-section fitting over the same, such rod portions acting to grip and strip the paper from the rule.

5. The combination with the movable gripper bars of a platen printing press, of a 125 perforating rule mounted on the form member of the press, and cross-extension rods on said bars, comprising two parallel rod

portions having a space formed between the same for allowing the perforating rule to enter therein in the movements of said rod portions, said rod portions having head portions at each end for holding the same together and for being connected to said bars and said rod portions being formed square in cross-section fitting over the same, such

rod portions acting to grip and strip the paper from the rule. 10

In testimony whereof, I, the said JOHN BALLARD WILLS, have hereunto set my hand.

JOHN BALLARD WILLS.
